UNITED STATES PATENT OFFICE.

ALFRED H. KIDNEY, OF ORANGE, NEW JERSEY, ASSIGNOR TO INTERNATIONAL CONCENTRATOR COMPANY, OF NEW YORK, N. Y., A CORPORATION OF NEW YORK

DRY ORE-CONCENTRATOR.

1,036,260.

Specification of Letters Patent. Patented Aug. 20, 1912.

Application filed October 31, 1911. Serial No. 657,703.

To all whom it may concern:

Be it known that I, ALFRED H. KIDNEY, a citizen of the United States, residing at Orange, in county of Essex and State of New Jersey, have invented certain new and useful Improvements in Dry Ore-Concentrators, of which the following is a specification.

My invention relates to an improvement in dry ore concentrators, and it relates to that class of concentrator in which regulated air force or suction is used to separate elements of lighter specific gravities, usually silicious compounds, from the heavy mineralized portions of ores in a granulated state, while being stratified according to their specific gravity on reciprocating tables and moving toward a discharge end. This has generally been indifferently accomplished by application of air force counter to the moving mass, creating a frictional sweeping movement of the particles of lighter specific gravity from the heavier bed mineral along its surface to a waste discharge. Or it has been done by air suction through perforations in raised portions of a reciprocating table, whereby the materials of lighter gravity were more or less drawn from the heavier by being sucked downwardly through said perforations and discharged in the usual manner. The first of the foregoing operations is primitive and crude, being subject to two unfavorable conditions, namely the volume of air force required to remove the greater portion of the lighter material acts also upon a considerable portion of the heavier, resulting in large losses; and, on the other hand, modification of the air force operates the other way, leaving a large quantity of waste in the mineral. The second method mentioned is also subject to unfavorable conditions, the perforations being arbitrary, or of fixed size, become more or less clogged, modifying the air force, and preventing a proportional amount of separating action. The feed being sensitive to the discharge, over-feed occurs, the granulated ore banks up on the table, overflows the perforations, and is sieved through in an unseparated state. Variation of speed also promotes the same conditions.

The object of my present invention is to separate the lighter gravity constituents of ores from the heavier by more direct and less

frictional action, to provide against unfavorable conditions heretofore specified, effect a higher degree of separation, and attain a greater volume of capacity. This I accomplish by the use of a vacuum chamber or suction box of conformable shape to a reciprocating table placed adjustably above the same with special reference to regulated proximity to the materials to be removed in harmony with the volume of air suction employed, the vacuum chamber or suction box being provided with a plate of proper area, which has elongated slots in the direction of its length, fixed rigidly to the forward bottom section of the box. A second correspondingly-slotted plate is adjustably placed upon the rigidly fixed plate within the box, and provided with means outwardly to regulate more or less the movement along its length, making available the full area of the said slots or fractions thereof in proportion to the cutting-off movement. In this structure, is provided means for creating large or small apertures as adapted to various sized ore granulations, and at the same time create a marked and varied proportional effect on the air force employed most favorable to perfection of operation and highest extraction. The regulated suction force being adjustably placed over the material of lightest specific gravity, it is separated from the under bed mineral by striking upward, operating with a minimum of friction and separating action on the heavier body.

Other distinctive features are an elastic partition between the top of the table and bottom of the suction box to prevent backing up of ore fed to the head of the table against the canvas throat or lining of the air suction passage, and which also accommodates itself to the independent up and down movement of the suction-box.

My invention further contemplates a pneumatic joint to prevent the passage of air between the sides of the frame and the suction box. Pneumatic tubes are received into the sides of the suction box along its length, making an air-tight junction with the inner sides of the table frame, and permitting free up and down adjustable movement.

My invention further consists in a tube connected with the bottom outlet of the feed hopper, and passing through the suction box to the table carrying ore fed to the

same, without affecting either the air current in the suction box or passage of the waste material to the discharge.

My invention further consists in certain novel features of construction and combinations of parts which will be hereinafter described and pointed out in the claims.

In the accompanying drawings:—Figure 1 is a longitudinal vertical section through one form which my improved concentrator takes, Fig. 2 is an enlarged transverse section, Fig. 3 is an enlarged detail in vertical, longitudinal section taken at the lower end of the table, Fig. 4 is an enlarged fragmentary section of the construction shown in Fig. 2, Fig. 5 is a horizontal section through the vacuum chamber or suction box, Fig. 6 is a plan view of the table showing the riffles thereon, Fig. 7 is a view of the slotted 70 adjusting grate, Fig. 8 is a bottom plan view of the suction box, Fig. 9 is a view showing the suction fan in a separating box.

A, represents the framework of the machine. In the bottom of the frame in the form illustrated in Fig. 1, the suction chamber B and the usual suction fan 1 are provided, and the partitions 2, 2, with the outlets for the tailings and middlings, if there be any.

30 The table 3, is suspended at its upper end on hangers 4, and at its lower end on means 5 and 6 for adjusting its inclination. The table is reciprocated by means of any approved head-motion 7. The upper surface of the table is provided with riffles 8, 8. These are preferably divided into two sets, separated a short distance from each other as illustrated by the smooth space 9 in Fig. 6. The table is closed at its upper end, and 40 open at its lower end 10 for the discharge of the concentrates. The table itself and the riffles are preferably imperforate.

A vacuum chamber or suction box 11 is hinged at its upper end as at 12 to the table, 45 and fitted at its sides between the sides 13, 13, of the table, as shown in Figs. 1, 2, and 4, and any approved means 14 is provided for adjusting the vacuum chamber or suction box with respect to the riffled surface of 50 the table, thereby regulating the space between the bottom of the vacuum chamber or suction box and the upper riffled surface of the table. To insure an air-tight joint at the sides, which is essential, the pneumatic tubes 15, 15, are placed in recesses formed to receive them in the sides of the vacuum chamber or suction box, as shown in Figs. 2 and 4, these being inflated at all times whereby the leakage of air at the sides is pre- 60 cluded, all air being drawn in through the discharge end of the table and thence upwardly through the bottom of the vacuum chamber or suction box through the narrow elongated slots 16, 16, provided for that purpose. To insure a proper distribution and

zig-zag or shilly-shallying of the ore in the space between the bottom of the vacuum chamber or suction box and the riffled surface of the table, the bottom of the former is ribbed as shown at 17, 17, in Figs. 2, 4, and 8, these ribs preferably alternating with the riffles as shown in Figs. 2 and 4, and the slots 16, 16, being through the ribs and not into the spaces between the ribs.

70 An adjustable grate 18 is arranged above the slotted portion of the floor or bottom of the vacuum chamber or suction box with slots 19, 19, corresponding in size and position with the slots 16, 16, of the bottom or floor of the vacuum chamber or suction box. Any approved means, such as the screw 20 at the lower end of the vacuum chamber or suction box, is employed for sliding the grate up or down to regulate or vary the size of the openings through the bottom of the vacuum chamber or suction box to suit requirements and conditions for the different grades of ore being treated.

To obtain a more delicate adjustment of the bottom of the vacuum chamber or suction box for purposes of alinement with respect to the table and to vary the size of the vacuum chamber, adjusting rods 27, 27, are provided. The rods 27 are connected to the bottom of the chamber and have their free ends passing loosely through the top where thumb-nuts 28, 28, are adapted to screw down upon them for raising the bottom, and springs 29, 29, encircling the rods between the top and bottom are provided 95 to maintain the alinement of the two members and to force the bottom downward when the nuts 28 are unscrewed. In some instances, it may be necessary to increase the suction in the chamber or to choke a portion only so that the air will pass at a greater velocity over that portion and this may be done by adjusting the bottom. It will be seen that the space above the riffles may also be adjusted in the same manner.

110 From the bottom of the hopper 21, a tube 22 leads through the suction box or vacuum chamber and discharges at the upper end of the table, as shown in Fig. 1, so that the feed of material from the hopper is not interrupted or interfered with by the upward currents of the lighter material drawn through the slots in the bottom of the vacuum chamber or suction box upwardly, as indicated by the arrows, and thence downwardly through the passage-way 23 into the chamber B, where the tailings and middlings, if there be any, are received and discharged in the usual manner.

115 An elastic partition 25 extends between the top of the table and bottom of the vacuum chamber or suction box to prevent backing up of ore fed to the head of the table against the canvas throat or lining 120 of the air suction passage 23, and which also

accommodates itself to the independent up and down movement of the suction box.

In Fig. 9, the suction chamber B is shown off at one side instead of being in the bottom of the frame A, and a tube 26 extends 5 from the vacuum chamber or suction box 11.

In operation, the table is reciprocated at the speed required, and the fan is rotated to create the desired suction. The air is 10 drawn in through the end 10 of the table, and up through slots 16 and 19. The size of these are regulated by adjusting the grate. The material is fed in the hopper 21, and down through the tube 22 on to the upper 15 rifled surface of the table where it is kept in a constant state of agitation. In the process of stratification, the lighter material, as it descends on the table above the heavier minerals, is sucked off to the nearest 20 slot 16, and thence through the vacuum chamber or suction box, in the direction indicated by the arrows, and out through the passage 23 into chamber B, and the clean 25 concentrates fall off at the end 10 of the table. In this way, a table of large capacity is provided for effectually separating the values from the gangue.

More or less slight changes might be resorted to in the form and arrangement of 30 the several parts described without departure from the spirit and scope of my invention, and hence I do not wish to be limited to the exact construction herein set forth, but:—

Having fully described my invention, what I claim as new and desire to secure by Letters Patent, is:—

1. In a dry ore concentrator, the combination with an imperforate shaking table, of 40 a vacuum chamber or suction box adjustably connected therewith, and having passage-ways therethrough, with means for circulating a current of air over the table, and thence into the vacuum chamber or suction box whereby to carry off the light particles 45 at the top, so that clean concentrates are left to discharge at the outer end of the table.

2. In a dry ore concentrator, the combination with an imperforate shaking table, of 50 a vacuum chamber or suction box adjustably connected therewith, the bottom of the chamber or box being adjustable to vary its parallelism or alinement with the upper surface of the table and having passage- 55 ways therethrough, with means for circulating a current of air over the table, and thence into the vacuum chamber or suction box whereby to carry off the light particles at the top, so that clean concentrates are left to discharge at the outer end of the table, and means for regulating the size of the passage-ways into the vacuum chamber or suction box.

3. In a dry ore concentrator, the combination with an imperforate shaking table, of a

vacuum chamber or suction box adjustably connected therewith, the bottom of the chamber or box being adjustable to vary its parallelism or alinement with the upper surface of the table and having passage-ways 70 therethrough, with means for circulating a current of air over the table, and thence into the vacuum chamber or suction box whereby to carry off the light particles at the top, so that clean concentrates are left to discharge 75 at the outer end of the table, and means for regulating the size of the passage-ways into the vacuum chamber or suction box, and means for regulating the inclination of the table.

4. In a dry ore concentrator, the combination with a reciprocating table and a vacuum chamber or suction box having openings therethrough located above the surface of the table, a hopper, and a tube extending 80 from the hopper through the vacuum chamber or suction box to the upper end of the table.

5. In a dry ore concentrator, the combination with a table having sides, of a vacuum 90 chamber or suction box fitted between the sides with air-tight joints, means for adjusting the vacuum chamber or suction box with respect to the surface of the table, and an elastic partition at the upper end of the 95 table extending between the head of the latter to the bottom of the vacuum chamber or suction box.

6. In a dry ore concentrator, the combination with a rifled table, of a vacuum chamber or suction box having a ribbed, slotted bottom, the ribs of which extend downwardly and alternate with the ripples on the table.

7. In a dry ore concentrator, the combination with a rifled table, of a vacuum chamber or suction box having a ribbed, slotted bottom, the ribs of which extend downwardly and alternate with the ripples on the table, and means for adjusting the vacuum 105 chamber or suction box with respect to the surface of the table.

8. In a dry ore concentrator, the combination with a rifled table, of a vacuum chamber or suction box having a ribbed, slotted 115 bottom, the ribs of which extend downwardly and alternate with the ripples on the table, means for adjusting the vacuum chamber or suction box with respect to the surface of the table, and means for varying 120 and regulating the size of the openings in the bottom of the vacuum chamber or suction box.

9. In a dry ore concentrator, the combination with a shaking table, of a vacuum chamber or suction box adjustably connected therewith, and having passage-ways therethrough, with means for circulating a current of air over the table, and thence into 125 the vacuum chamber or suction box whereby

to carry off the light particles at the top, so that clean concentrates are left to discharge at the outer end of the table, and means for regulating the size of the vacuum chamber thereby controlling the velocity of the air current.

10. In a dry ore concentrator, the combination with a riffled table, of a vacuum chamber or suction box having a ribbed, slotted bottom, the ribs of which extend downwardly and alternate with the riffles on the table, and means for adjusting the vacuum chamber or suction box with respect to the table, and means for raising 15 and lowering the ribbed slotted bottom to obtain a more delicate adjustment between the ribs and the surface of the table.

11. In a dry ore concentrator, the combination with a shaking table, of a vacuum chamber or suction box adjustably connected therewith, and having passage-ways therethrough, with means for circulating a current of air over the table, and thence into the vacuum chamber or suction box 25 whereby to carry off the light particles at the top, so that clean concentrates are left to discharge at the outer end of the table, and means for varying the space at different points between the table surface and the bottom of the vacuum chamber or suction-

box and means for varying the current over different parts of the table.

12. In a dry ore concentrator, the combination with a table, of a vacuum chamber or suction box, the bottom of which is slotted, and means for adjusting and regulating the size of the slots, the bottom being bodily adjustable whereby the parallelism with the surface of the table may be regulated.

13. In a dry ore concentrator, the combination with a table, of a vacuum chamber or suction box having an adjustable bottom, and means for raising and lowering one end of the vacuum chamber or suction-box with respect to the corresponding end of the table.

14. In a dry ore concentrator, the combination with a riffled table, of a vacuum chamber or suction-box having a ribbed slotted bottom, the ribs of which extend downwardly, and means for adjusting said bottom with respect to the sides and top of the vacuum chamber or suction-box.

In testimony whereof I affix my signature, in the presence of two witnesses.

ALFRED H. KIDNEY.
